UNITED STATES PATENT OFFICE.

LOUIS A. VEIGEL, JR., OF NEWARK, NEW JERSEY.

FLEXIBLE BRACELET.

Application filed January 22, 1921. Serial No. 439,081.

To all whom it may concern:

Be it known that I, LOUIS A. VEIGEL, Jr., a citizen of the United States, residing in Newark, in the county of Essex and State 5 of New Jersey, have invented certain new and useful Improvements in Flexible Bracelets, of which the following is a specification.

This invention has as its main object to 10 provide a bracelet or like article, comprised of a plurality of independent elements so linked or joined as to present an article having desirable flexibility and of neat and attractive appearance.

15 A further purpose is to produce a bracelet made entirely of metal, possessing the characteristics of symmetry and lightness, durability and strength, and which can be constructed and assembled in a rapid and 20 economical manner by automatic machinery without the use of solder, rivets or like fastening means.

These and other analogous objects are attained by the novel design, construction 25 and combination of parts hereinafter described and shown in the accompanying drawings, forming an essential part of this disclosure, and in which:—

Figure 1 is a perspective view showing 30 a bracelet made in accordance with the invention.

Figure 2 is a plan view of the link blank employed drawn to an enlarged scale.

Figure 3 is a perspective view showing 35 a pair of the links connected, parts being broken away to disclose the joint construction.

Figure 4 is a perspective view of one of 40 the link connections.

Figure 5 is a plan view looking from the inner side of a pair of links made in a modified form and joined by a different connection.

Figure 6 is a longitudinal sectional view 45 taken on line 6—6 of Figure 5.

Stated in general terms each link is formed from a cross-shaped thin metallic blank, its central portion constituting the face of the link.

Opposed lateral extensions having slightly 50 converging angular edges are bent at right angles forming the link sides, while the two remaining extensions are curled to engage the opposed elements of connections in such

manner as to freely pivot thereon within 55 the limit of the aforesaid angular edges of the sides.

Referring now more particularly to Figs. 1 to 4 of the drawings, showing the preferred embodiment of the article, the blank 60 as indicated in Figure 2 will be seen to consist of thin flat plate approximately in the shape of a Maltese cross, its central portion 10 forming the exposed face of the link, having upon opposite sides symmetrical extensions 11, their lateral edges 12 being reduced in width converging outwardly 65 for a purpose further on apparent.

Other projections 14 extend from the center plate 10 at right angles to the extensions 11, and are slightly longer with parallel side edges.

The projections 14 are reduced in thickness, tapering from their base to the extremities, and are centrally recessed presenting open spaces 15 extending inward to 75 the central element 10. See Figure 3.

The four side elements 11 and 14 are bent vertical with reference to the plate 10, presenting an open rectangular box-like structure, its end elements being bifurcated as 80 indicated.

The connecting elements, as shown in Figure 4, consist of thin flat blanks shaped like the capital letter H, their central transverse elements or bars 16 being suited to freely enter the slots 15 while the longitudinal members 17 are received lengthwise between the upright sides 11 of the links and the spaces 18 between the members 17 are sufficiently wide to accommodate 90 the forks of two adjacent end elements 14 holding a pair of links so that the plates 10 of each are in close proximity.

These forks 14, which may have been 95 given a slight initial curl, are coiled so as to envelop the elements 17 but not so tightly as to prevent them acting as pivots on which the links may turn.

It will now be seen that if the extensions 100 11 had parallel edges the links would be disposed in a straight unyielding row, but due to the incline 12 of their edges, the links can be formed into a curve, such as is indicated in Figure 1, necessary for the purpose 105 mentioned.

It is to be further noted that if the elements of the blank be sharply bent a sub-

stantially continuous surface is presented upon the exterior and also the sides of the bracelet.

In the modification, shown in Figs. 5 and 5 6, a similar blank is used consisting of center plates 20 provided with like side extensions 21 having angular side edges 22.

The end projections 24 are similarly reduced in thickness towards their ends, which 10 as before extend outward to a greater distance than the elements 14, and in place of being slotted are reduced in equal amounts on both side edges, being approximately one-half the width of the plate 20.

15 The connecting elements used in connection with this form of link is comprised of a flat rectangular plate, having an opening of the same shape, the longitudinal members 25 extending between the side elements of 20 the link and have coiled about them the end elements 24 which have been passed through the opening 26 of the connector plate as is clearly shown.

Like the preferred embodiment substantially no side movement or lateral bending can take place and in both types the joints are strong and securely held in their original assembled relation.

30 No special clasp is required and no springs, rivets, solder or brazing used.

It will be obvious that any of the precious metals may be used or less expensive material employed finally finished and plated after assembling as may be preferred.

35 While certain preferred embodiments of this device have been shown and described, it will be understood that changes in the form, arrangements, proportions, sizes and details thereof may be made without departing from the scope of the invention as defined in the appended claims.

Having thus described my invention, what I desire to secure by Letters Patent and claim, is:—

45 1. An article of the character described, comprising a plurality of box-like links formed of thin sheet metal, the end elements being coiled inwardly, and connecting elements partially enveloped in the coiled ends 50 of adjacent links.

55 2. An article of the character described, comprising a plurality of rectangular links having raised side and end elements, said end elements being reduced in thickness towards their extremities and coiled under the face of the link presenting open loops, and connecting elements having portions engaged in the loops of proximate links in such manner as to permit pivotal motion.

60 3. An article of the class described, comprising a series of like hollow rectangular links having flat faces and raised side and end elements, the lateral edges of said side elements being convergently inclined towards their ends, inturned loops formed by

said end elements, and connecting elements pivotally engaged in said loops.

4. An article of the class described, comprising a series of like hollow rectangular links having flat faces and sharply turned 70 side and end elements, said side elements having inclined edges and said end elements being reduced in thickness, coiled loops formed by said end elements extending under the face elements of the links and integral 75 connecting means pivotally disposed in the loops of proximate pairs of links.

5. An article of the class described comprising a plurality of links each integrally formed to present a rectangular plate having raised side and end elements, said end elements being relatively narrower and longer than said side elements, reduced in thickness and coiled inwardly presenting eyes, and a rectangular metal frame having 80 its longer sides disposed within the eyes of 85 adjacent links.

6. An article of the class described comprising a plurality of links each integrally formed to present a rectangular plate having 90 raised side and end elements, said side elements having convergently inclined lateral edges, said end elements being reduced in thickness and of lesser width than said plate, eyes formed at the ends of the links by coiling 95 said end elements inwardly and an open rectangular frame having its longer members engaged in the eyes of adjacent links and connecting therebetween in such manner as to permit the link to limitedly pivot 100 thereon.

7. A flexible chain adapted for use as a link-bracelet, consisting of a plurality of main link-members and intermediate connecting link-members, each connecting link-member being made in the form of an open frame comprising a pair of laterally extending end-members, and a pair of longitudinally extending side members, and each main link-member comprising a main body-plate 105 provided with laterally projecting side extensions and longitudinally projecting end-extensions, said end-extensions being bent at right angles to said body-plate, said side-extensions having their marginal edge-portions also bent at right angles to said body-plate to provide a pair of longitudinally extending flanges, said end-extensions being of 110 such width so as to provide receiving spaces between the edges of the end extensions and 115 said longitudinally extending flanges, said longitudinally extending flanges in which portions of said longitudinally extending side members of a connecting link-member are adapted to be arranged, the right-angled portions of the end-members 120 of the main link-members being inserted between the longitudinally extending side-members of the connecting link-member and bent around the laterally extending end-members of said link-members so as to form 125

130

loops, all arranged for articulated or pivotal connection of the various connecting link-members with the various main link-members.

5 8. A flexible chain adapted for use as a link-bracelet, consisting of a plurality of main links and intermediate connecting links, each main link comprising a main body-plate provided with angularly disposed and longitudinally extending flanges, and with angularly disposed and laterally extending end-members, and each connecting link comprising a rectangularly formed

open frame through which said laterally extending end-members are inserted and bent 15 over so as to form loops, all arranged for articulated or pivotal connection of the various main links with said connecting links.

This specification signed and witnessed 20 this twentieth day of January, 1921.
